UNITED STATES PATENT OFFICE

2,485,427

PRESSURE FIRED COMBUSTION CHAMBER

Harry M. Arnold, Golden, Colo.

Application February 27, 1946, Serial No. 650,410

7 Claims. (Cl. 60—45)

1

This invention relates to new and useful improvements in steam generators and more particularly to a pressure fired combustion chamber so constructed and arranged that extremely high temperature superheated steam and products of combustion are generated and delivered to the cylinder of my steam engine described and illustrated in my co-pending patent application No. 611,117 on Cylinder head for superheated steam engine, now Patent No. 2,464,112. Heretofore superheated steam has been produced by passing steam through tubes heated by the fire or products of combustion from the boiler furnace. The practical limit of steam temperatures so produced is about 1200° F.

The general object of my invention is to combust gas or liquid fuel directly into the steam from the boiler so that steam temperatures of 1500° F. to 3600° F. can be produced. Several attempts have been made in the past to operate a steam engine by combusting fuel under pressure. These attempts have been unsuccessful because:

1. The products of combustion were mixed with the water in the boiler and a low temperature mixture of saturated steam and products of combustion were produced.

2. The steam and products of combustion were conducted through long pipe lines or were subjected to a water cooled surface before they reached the cylinder of the engine so that the working fluid in the engine was at a low temperature level and the energy available as work was proportionately little.

I combust my fuel and air under pressure within a refractory lining which conducts heat through it very slowly thereby retaining the high temperature of the combustion. The high temperature steam and products of combustion are conducted through very short pipes and overhead valves, and onto the piston of the engine. When the engine is operating at high speed, as is common practice nowadays, the steam and products of combustion will be extremely hot when they expand behind the piston of the engine and the energy available is proportionately great.

This invention also consists of certain other features of construction and in the arrangement and location of the compressor necessary for supplying compressed air for combustion. The novel features of the invention are illustrated in the accompanying drawings and specifically pointed out in the appended claims.

In describing the invention in detail, reference will be had to the drawings wherein like numbers

2

denote like or corresponding parts throughout, and in which:

Figure 1 is a longitudinal part sectional view of a double acting engine, combustion chamber and built-in air compressor.

Figures 2 and 3 are transverse sectional views taken respectively on the lines 2—2 and 3—3 of Figure 1, and

Figure 4 is a similar view taken on a line 4—4 of Figure 1 and showing a plan view of the lining used at the top of the combustion chamber.

Referring to Figure 1 of the drawings the cycle of operation is explained. Cold air is drawn in through the pipe 1 and onto the top of the compressor piston 2. On the up-stroke of the piston 2 the air is forced from the top side of the piston 2 and enters the small chamber 3 around the trunk of the piston 2 where it is again compressed by the piston 2 on the following down-stroke.

20. The air is forced from the chamber 3 through the valve 3a and into the pipe line 4. From the pipe 4 the air may go to the air storage tank 6 or pass through the pipe line 30 to the valve 29 where its flow to the combustion chamber 8 is regulated. A very simple type of air atomizing fuel burner 5 is here illustrated. Gas or liquid fuel enter through the pipe 7 and its flow into the burner 5 is governed by the control valve 7a. A powdered coal burner may be used in special cases. The air and fuel are mixed within the tube of the burner 5 and are blown into the combustion chamber 8 where ignition of the mixture is started by an electric firing plug 11. The character of the flame can be observed through the sight tube 12.

35. When the fuel burner 5 is first started it may be desirable to expel the products of combustion to the atmosphere. A relief valve 5a is provided at a convenient point for this purpose. As soon as the combustion is observed to be satisfactory 40 the valve 5a can be closed and the engine 26 started. For a little while the engine will operate as a hot air engine. The engine 26 is of water cooled construction and includes a piston 45 (not shown) connected to the piston 2 of the compressor by a rod 26a. The compressor 2 will supply air for combustion and gradually recharge the storage tank 6 for reserve. When the engine 26 becomes hot and the refractory lining 9 be-

comes white hot, heat will be imparted to the water in the jacketing system 13 of the engine 16 and some heat will pass through the boiler shell 15 and evaporate the water in the jacketing system 15 of the boiler 17. The saturated steam 55 produced in the water jacket 15 will rise to the

dome 19 and will enter the pipe 20. A valve 20a will throttle the flow of steam to the head 21a where it is distributed radially to the channels 21 in the refractory lining 9. The steam is conducted through the long slender passage ways 21 in the refractory 9 to the lower part of the combustion chamber 8 where it issues from small openings 22 into the combustion chamber 8 and mixes directly with the products of combustion. The steam will be partly superheated when traveling through the channels 21 in the refractory lining 9 so that it will be dry and hot when it enters the combustion chamber 8.

The high temperature mixture of superheated steam and products of combustion pass through very short pipes 23 to the valve chests 24 of the engine 26. The circulating system 13 is provided around the end portions of the cylinder 26 and also in the heads 25 as will be seen in my said Patent No. 2,464,112.

A valve 10a in the water pipe line 10 regulates the flow of water to the circulating system 13 of the engine and through the pipe 14 into the boiler 17 where it mixes with the water in the water jacket 15. The desired water level may be maintained in the water glass 18. A pop-off valve 18a is provided in the boiler shell 17 to relieve excess steam pressure should it arise.

In order to afford an even distribution of heat to the two pipes 23 the lower pipe 23 draws its steam through the refractory tube 9a from a point about half-way between the two pipes 23.

Details of the channels 21 can be seen in Figure 2. Figure 4 is a top view of the refractory head 21a showing the radial passage ways 21b which connect with the passage ways 21 of Figure 2.

The engine piston, (not shown) is alternately pushed from one end of the cylinder to the other end and the used steam is exhausted into the exhaust 28. The pipe 10 passes through the exhaust 28 so the water entering the circulating system 13 is hot.

The jacketing system 31 of the compressor should be supplied with cool water to help cool the air being compressed so that less work is required to supply the compressed air. When very high temperature steam is used in the engine about 1 horsepower out of 6 produced by the engine will be required to compress the air used for combustion.

The temperature of the steam and products of combustion going to the engine may be governed in two ways:

1. The refractory lining 9 may be made thick so very little heat will be conducted through to the inner boiler shell 16 thereby evaporating very little water in the leg 15.

2. The throttle valve 20a can be used to govern the flow of steam to the combustion chamber 8 allowing the surplus steam to pop off to the atmosphere through the valve 18a.

The refractory lining 9 and the refractory head 21a must be made a little smaller than the inside of the shell 16 to allow for expansion when it becomes very hot.

This apparatus for generating high temperature and high pressure steam can be made very light and compact as compared with modern boiler plants. The entire boiler 17 and the engine 26 should be neatly encased in asbestos or other heat non-conducting material to avoid loss of heat to the atmosphere.

The lower part of the engine is enclosed in an oil case 32 and the connecting rod is equipped

with double row roller bearings 33 while two bearings of single row rollers 34 are provided for the crank shaft 36. The eccentric 35 actuates the valves of the engine 26 throughout the pitman rod 35a.

Like any steam engine this engine has a reserve of energy stored in the water in the boiler 17 and in heat energy stored in the refractory lining 9 so that the engine will run very smoothly when used in direct drive where gears or other driving mechanism is to be eliminated. This steam engine will deliver more energy from a gallon of fuel oil or crude oil than is now obtained with the Diesel engine.

While the drawings show the invention applied to a reciprocating engine of the type shown, it will of course, be understood that the high temperature steam generator can be applied to the single-acting piston engine as well as to engines having two or more cylinders made together.

It is to be understood that changes may be made in the construction and in the combination and arrangement of the several parts provided such changes fall within the scope of the appended claims.

Having described my invention, what is claimed as new is:

1. A steam boiler comprising a cylindrical shell supported in an upright position and having a water jacket therein open at its top for communication with the top of the shell, a refractory lining in the boiler closed at one end and forming a combustion chamber in the shell, a steam chamber in the top of the shell, longitudinal steam passages communicating at their upper ends with the steam chamber, ports in the lining connecting the lower ends of the passages with the combustion chamber to feed steam to the combustion chamber, a burner in the combustion chamber, and an outlet leading from the combustion chamber.

2. A steam boiler comprising a cylindrical shell supported in an upright position, a refractory lining in the shell closed at its top to form a combustion chamber in the shell, a water jacket between the walls of the lining and the walls of the shell and having an open top to provide a steam chamber in the top of the shell above the top of the combustion chamber, vertical steam passages leading from the steam chamber to the lower portions of the combustion chamber, a burner in the bottom of the combustion chamber, and an outlet leading from the combustion chamber.

3. A steam boiler comprising a cylindrical shell supported in an upright position, a refractory lining in the shell closed at its top to form a combustion chamber in the shell, a water jacket between the walls of the lining and the walls of the shell and having an open top to provide a steam chamber in the top of the shell above the top of the combustion chamber, vertical steam passages in the vertical walls of the lining leading from the steam chamber to the lower portion of the combustion chamber, a burner in the bottom of the combustion chamber, and an outlet leading from the combustion chamber.

4. A steam boiler comprising a cylindrical shell supported in an upright position, a refractory lining in the shell closed at its top to form a combustion chamber in the shell, a water jacket between the walls of the lining and the walls of the shell and having an open top to provide a steam chamber in the top of the shell above the

top of the combustion chamber, vertical steam passages in the outer vertical walls of the lining leading from the steam chamber to the lower portion of the combustion chamber, a burner in the bottom of the combustion chamber, and an outlet leading from the combustion chamber.

5. A steam boiler comprising a cylindrical shell supported in an upright position, a refractory lining in the shell closed at its top to form a combustion chamber in the shell, a water jacket between the walls of the lining and the walls of the shell and having an open top to provide a steam chamber in the top of the shell above the top of the combustion chamber, vertical steam passages between the lining and the waterjacket communicating at their lower ends with the combustion chamber, a tube extending from the top of the lining to the steam chamber to admit steam to the passages, a burner in the bottom of the combustion chamber, and an outlet leading from the combustion chamber.

6. A steam boiler comprising, a double walled cylindrical shell, the space between the walls forming a water jacket, the inner wall having a top closure spaced from the top of the outer wall, a refractory lining in the shell, closed at one end, forming a combustion chamber, the space between the closed ends of the inner and outer walls of the shell providing a steam chamber, the lining having longitudinally extending grooves in its outer surface, whose ends are in communication with the steam chamber and with the combustion chamber, said grooves forming passages for steam from the steam chamber to the combustion chamber, and a burner positioned in the

5

combustion chamber at the lower end thereof, there being at least one outlet communicating the combustion chamber with the outside of the shell.

7. A steam boiler comprising a cylindrical shell, a refractory lining in the shell closed at one end to form a combustion chamber in the shell, a water jacket between the walls containing the lining and the walls of the shell and having an open space to provide a steam chamber over the top of the wall enclosing the combustion chamber, a steam passage connecting the steam chamber with the closed end of the refractory lining, longitudinal steam passages in the refractory lining leading from the closed end to the burner end of the combustion chamber, inlets at one end communicating said passages with the combustion chamber, a burner in one end of the combustion chamber and at least one outlet communicating the combustion chamber with the outside of the shell.
